US00D989143S

(12) **United States Design Patent** (10) **Patent No.:** **US D989,143 S**
Huo (45) **Date of Patent:** **** Jun. 13, 2023**

(54) **AUTOMATED GUIDED TRANSPORT VEHICLE**

(71) Applicant: **HANGZHOU HIKROBOT CO., LTD.**, Hangzhou (CN)

(72) Inventor: **Ruixiang Huo**, Hangzhou (CN)

(73) Assignee: **HANGZHOU HIKROBOT CO., LTD.**, Hangzhou (CN)

(**) Term: **15 Years**

(21) Appl. No.: **29/770,656**

(22) Filed: **Feb. 15, 2021**

(30) **Foreign Application Priority Data**

Aug. 24, 2020 (CN) 202030487963.5

(51) **LOC (14) Cl.** **15-99**

(52) **U.S. Cl.**

USPC **D15/199**

(57) **CLAIM**

The ornamental design for an automated guided transport vehicle, as shown and described.

DESCRIPTION

FIG. 1 is a front elevation view of the present design according to my new design;

FIG. 2 is a back elevation view thereof;

FIG. 3 is a left side view thereof;

FIG. 4 is a right side view thereof;

FIG. 5 is a top plan view thereof;

FIG. 6 is a perspective view thereof; and,

FIG. 7 is another perspective view thereof.

1 Claim, 3 Drawing Sheets
